UNITED STATES PATENT OFFICE.

JULIUS C. CHRISTIANSEN, OF NEW YORK, N. Y.

MARINE VESSEL.

1,408,270.

Specification of Letters Patent. Patented Feb. 28, 1922.

Application filed June 28, 1920. Serial No. 392,339.

To all whom it may concern:

Be it known that I, JULIUS C. CHRISTIANSEN, a citizen of Germany, and a resident of the city of New York, in the county of 5 New York and State of New York, have invented certain new and useful Improvements in Marine Vessels, of which the following is a specification.

The present invention relates to improvements in marine-vessels, and the invention resides more particularly in the hull structure of small craft, such as motor boats, sail boats and small yachts.

One of the objects of the invention is to 15 produce a flat bottomed hull, having simple means for diminishing the resistance between the water and the vessel, when moving through the water, and effective in increasing the speed.

Another object of the invention is to 20 produce a normally open boat having a collapsible cabin or top, that can be conveniently and quickly set up, when needed.

A further object of the invention is to 25 utilize the otherwise unused stern part of the hull by locating therein a water tank, for holding fish, etc., if the vessel is used as a fishing boat.

A further object of the invention is to 30 provide a marine-vessel, that is capable of being used as an ice-boat or sleigh.

With these and other objects in view, which will more fully appear as the nature of the invention is better understood, the 35 same consists in the combination, arrangement and construction of parts hereinafter described, pointed out in the appended claims and illustrated in the accompanying drawings, it being understood that many 40 changes may be made in the size and proportion of the several parts and details of construction within the scope of the appended claims, without departing from the spirit or sacrificing any of the advantages 45 of the invention.

Two of the many possible embodiments of the invention are illustrated in the accompanying drawings, in which:—

Figure 1 is a side elevation of a boat 50 hull constructed in accordance with the present invention; Fig. 2 is a top plan view of the same; Fig. 3 is a front elevation thereof; Fig. 4 is a rear elevation of the same; Fig. 5 is a section taken on line 5—5 55 of Fig. 1; Fig. 6 is a side elevation of the vessel, partly in section, showing the cabin

or top in its extended position; Fig. 7 is a side elevation of a modified hull construction; and Fig. 8 is a top plan view of the hull shown in Fig. 7.

Referring now first to Figs. 1 to 6, inclusive, of the drawings, the numeral 10 indicates the hull of a small craft, including a bottom 11 that is flat from the stern-post 12 forward to a transverse vertical 60 plane 13, at which the midship body of the vessel joins the bow part 14 thereof. From this plane forward the bottom rises toward the stem 15, it being slightly curved both longitudinally and transversely. The longitudinal edges of the bottom converge from the plane 13 toward the stem 15, and also from the said plane toward the stern-post 12. The stem 15 is inclined forward 65 and is connected by a keel 16 with the stern-post 12, the said keel projecting below the surface of the bottom from the plane 13 approximately to the stern-post. The sides 17 of the hull rise substantially vertically throughout the length of the vessel, so that 70 transverse cross-sections of the same from the stern-post to the plane 13 are of substantially rectangular configuration. From the plane 13 forward the bases of the cross-sections are slightly curved, but are otherwise 75 substantially of rectangular configuration. The curved portion of the bottom joins the stem 15 in a plane that is substantially in the water line of the vessel.

From the foregoing it appears that the 80 largest transverse cross-section of the vessel is disposed in the plane 13, that is to say in a transverse vertical plane in which the bow part of the vessel joints the midship body thereof, the said midship body decreasing in width gradually toward the stern part of the hull, and the said stern part terminating in a vertical post. In other words, the stern part, in horizontal 85 cross-section, is in the form of an inverted 90 wedge, the point of which is constituted by the post 12.

The construction of the transverse frames 18 of the vessel need not be described herein, as the same does not form part of the 95 present invention. These frames are, in the construction shown in Figs. 1 to 6, inclusive, of the drawings, disposed in vertical planes, as usual in constructions of this type.

The vessel is of the open boat type, it 100 being provided, if necessary, in its bow part

with a deck 19 and in its stern part with a deck 20. Between these decks is disposed the cock-pit.

Immediately in rear of the deck 19, there 5 is mounted upon one of the transverse frames 18 a partition-like board 21, the said board being rotatable on trunnions 22, that are mounted in the said frame substantially in the plane of the deck 19. This board is 10 normally disposed within the hull, as shown in Fig. 5 of the drawings, partitioning off the bow part 14 from the midship body, whereby a bunk- and storage-room 19' is obtained. In front of the after deck 20 is 15 mounted, upon the adjacent frame 18, a transverse stringer 23, upon which is adapted to be placed a standard 24, rising from the said stringer, as shown in Fig. 6 of the drawings, and adapted to be secured there- 20 to in any suitable manner. The board 21 is adapted to be extended above the deck 19 vertically, and on the said board and standard 24 is placed, in the longitudinal center line of the vessel, a spar 25, for instance the 25 mast of the vessel, if the latter is of the sailing vessel type. A fabric piece 25', such as a tarpaulin or a sail is then placed over the said spar and secured to the free edges 26 of the board 21 and to the sides of the hull 30 all along the cock-pit, whereby a top is provided for the said cock-pit, when required. When there is no use for the top, the fabric piece 25' is removed and the board 21 folded into the hull, the standard 24 being either 35 taken off the stringer 23 or used as a flag pole.

Below the deck 20 is placed a, preferably, open water tank 27, into which fish are thrown, as they are being caught.

40 By reason of the fact that the largest transverse cross-section of the midship body of the hull is disposed in a vertical transverse plane, in which it joins the bow part 45 of the vessel, the resistance between the water and vessel, when moving through the water, is greatly decreased, with the result that its speed is increased. The slightly curved portion of the vessel bottom constitutes an inclined plane, which has a tendency to raise the boat out of the water and to diminish the amount of submerged surface, that would oppose resistance to speed movement through the water.

55 A modification of the invention is illustrated in Figs. 7 and 8 of the drawings, differing from the one above described in that the stern post 12' extends at an acute angle to the keel, it being inclined forward

and connecting the midship body of the 60 hull with the said keel. The stern body 28 of this hull constitutes thus a true wedge, decreasing even to a greater degree the resistance between the water and the vessel. Otherwise the construction is the same as 65 of the craft above described, with the exception that the after deck 20 is in this case missing.

In the hull, shown in Figs. 7 and 8 of the drawings, the transverse frames 18 are disposed in planes substantially parallel to the stern post 12'. The purpose of this arrangement is to increase the resistance of these frames to stresses to which they are subjected in the line of motion by the wa- 70 ter, when moving therethrough.

As appears from Figs. 3 and 4, there are two auxiliary keels 16' mounted upon the flat portion of the bottom 11, one on each side of the keel 16. These auxiliary 80 keels constitute runners, on which the boat slides when used as an ice-boat or sleigh. This construction may also be applied to the boat shown in Figs. 7 and 8.

It will be understood that the boats herein described may be propelled by sails, motors or oars, and may be used as pleasure boats, fishing-boats, house-boats, etc.

Attention is also called to the fact that, while herein the boats have been described 90 as belonging to the small craft type, the general hull construction described may be made use of in building marine vessels of any desired size.

What I claim is:—

1. A marine-vessel including a hull having a straight bottom from its vertical stern post to a transverse plane where the midship body joins the bow section of the hull said bottom being inclined upward from said plane to the stem of the bow, the sides of said hull being straight from the bottom up.

2. A marine vessel according to claim 1 having 1 or more keels.

3. In a marine-vessel according to claim 1 the longitudinal edges of the straight section of said bottom converging from said plane to said stem and also from said plane to said stern.

4. In a marine-vessel according to claim 1 said stem being forwardly inclined.

Signed at New York, in the county of New York and State of New York this 15th day of June, A. D. 1920.

JULIUS C. CHRISTIANSEN.
